UNITED STATES PATENT OFFICE.

MARY CHASE BARON, OF HAMPTON MEADOWS, RHODE ISLAND.

DESIGN FOR A BROODER-HOOD.

57,573.

Specification for Design.

Patented Apr. 26, 1921.

Application filed August 26, 1920. Serial No. 406,239. Term of patent 14 years.

To all whom it may concern:

Be it known that I, MARY CHASE BARON, a citizen of the United States, residing at Hampden Meadows, county of Bristol, and State of Rhode Island, have invented a new, original, and ornamental Design for a Brooder-Hood, of which the following is a specification, reference being had to the accompanying drawing, forming part thereof.

Figure 1 is a perspective view of a brooder hood.

Fig. 2 is a longitudinal central sectional elevation through the brooder hood.

I claim:

The ornamental design for a brooder hood, as shown.

MARY CHASE BARON.
